US00D895060S

(12) **United States Design Patent** (10) Patent No.: **US D895,060 S**
Qin et al. (45) Date of Patent: ** Sep. 1, 2020

(54) **WATER CHILLER**

(71) Applicant: **HAN'S LASER TECHNOLOGY INDUSTRY GROUP CO., LTD.**, Shenzhen, Guangdong (CN)

(72) Inventors: **Chaozhen Qin**, Guangdong (CN); **Deluo Wen**, Guangdong (CN); **Zhaoyong Guo**, Guangdong (CN); **Qitao Lue**, Guangdong (CN); **Yunfeng Gao**, Guangdong (CN)

(73) Assignee: **HANS'S LASER TECHNOLOGY INDUSTRY GROUP CO., LTD.**, Shenzhen (CN)

(**) Term: **15 Years**

(21) Appl. No.: **29/636,814**

(22) Filed: **Feb. 12, 2018**

(51) LOC (12) Cl. **23-01**

(52) U.S. Cl.

USPC **D23/209**; D15/79

(58) **Field of Classification Search**

(57) **CLAIM**

The ornamental design for a water chiller, as shown and described.

DESCRIPTION

FIG. 1 is a perspective view of a water chiller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures are included for the purpose of illustrating portions of the water chiller which form no part of the claimed design.

1 Claim, 7 Drawing Sheets
